R. W. Bois

UNITED STATES PATENT OFFICE.

THOMAS J. WEAVER, OF COLUMBIANA, ALABAMA.

SELF-LUBRICATING AXLE.

SPECIFICATION forming part of Letters Patent No. 427,451, dated May 6, 1890.

Application filed November 12, 1889. Serial No. 330,002. (No model.)

To all whom it may concern:

Be it known that I, THOMAS J. WEAVER, a citizen of the United States, residing at Columbiana, in the county of Shelby, and State 5 of Alabama, have invented certain new and useful Improvements in Self-Lubricating Axles; and I do hereby declare the following to be a full, clear, and exact description of the invention, such as will enable others skilled 10 in the art to which it appertains to make and use the same.

My invention relates to self-lubricating vehicle-axes; and my object is to provide more efficient and durable means for accomplishing this end than have hitherto been known.

With this purpose in view my invention consists in certain peculiar features of construction and combinations of parts, more fully described hereinafter, and pointed out 20 in the claims.

Referring to the accompanying drawings, Figure 1 represents a longitudinal section of my improved axle, and Fig. 2 a detail view of the sponge and attachments.

25 The reference-letter A indicates the main portion of the axle, which is preferably made hollow throughout and serves as a reservoir for the oil. Apertures *aa* are formed in this portion of the axle, through which the oil or 30 other lubricant is introduced. These holes are made near the spindles in case the axle may not be hollow throughout or may be bent, and they are provided with taps *a'a'*, which effectually close them and prevent the oil 35 from escaping. The spindles *B* are also made hollow and are provided on their outer ends with nuts *C*, which have solid heads, and bowl-shaped cavities *cc* in their inner ends. A sponge *D* or like absorbent material is 40 placed within the spindle, and a wire *d* passes through said sponge, being bent at either end into rings *e*. Washers or disks *c*, preferably made of leather, are interposed on said wire between the sponge and rings *e* and serve to 45 preserve the shape of the sponge and prevent it from swelling laterally. The outer wire ring projects into the inner cavity of the nut, while the inner one enters the hollow axle-

body. The sponge can be readily withdrawn from the spindle by means of the ring *e* 50 when it is desired to replace it or for any other purpose. Small perforations *b b* are made in the spindles, through which the oil oozes to lubricate the axle.

The preferred mode of constructing my device having been set forth, I will now describe 55 its operation. The hollow axle-body is first filled with oil, which then runs into the hollow spindle, and swells the sponge until it fills and tightly fits the spindle. When the 60 vehicle is in motion, the axle-box, revolving around the spindle, causes the oil to ooze through the perforations *b* and lubricate the axle. When the vehicle stops, the axle-box 65 closes the perforations and stops the flow of oil. By this arrangement the axle will lubricate itself until all the oil in the hollow axle-body is exhausted, when it can be refilled through the apertures *a a*.

It is evident that many slight variations in 70 the construction and arrangement of parts of my invention might be resorted to without departing from its spirit and scope; hence I do not confine myself to the precise construction shown; but,

Having thus described my invention, what 75 I claim as new, and desire to secure by Letters Patent, is—

1. In a self-lubricating axle, the combination 80 of a hollow spindle provided with perforations, a sponge or like absorbent material arranged to fill said spindle, and disks for confining said sponge, in the manner and for the purpose set forth.

2. In a self-lubricating axle, the combination 85 of a hollow spindle having perforations, a sponge or like absorbent material arranged to be placed within said spindle, disks of suitable material for confining said sponge, and a wire or rod passing through said sponge and 90 said disks and confining the same in place, substantially as described.

3. In a self-lubricating axle, the combination 95 of a hollow spindle having perforations, a sponge arranged to fill said spindle, a wire passing through said sponge, disks on said

wire, and rings formed at opposite ends of the wire for confining said disks, substantially as described.

4. In a self-lubricating axle, the combination of a hollow axle-spindle having perforations, a sponge or like absorbent material to fill said spindle, a wire passing through said sponge, rings formed at either end of said wire, disks interposed between said sponge

and said rings, and nuts for closing the ends of said spindle and having hollow inner ends, as and for the purpose described.

In testimony whereof I affix my signature in presence of two witnesses.

THOMAS J. WEAVER.
